UNITED STATES PATENT OFFICE.

MARCEL ACHILLE VIOLET, OF LEVALLOIS-PERRET, FRANCE.

MULTICYLINDER TWO-STROKE MOTOR.

1,346,069.

Specification of Letters Patent.

Patented July 6, 1920.

Application filed November 21, 1917. Serial No. 203,195.

To all whom it may concern:

Be it known that I, MARCEL ACHILLE VIOLET, a citizen of the Republic of France, resident of 67 Rue Rivay, Levallois-Perret, 5 Seine, in the said republic, have invented certain new and useful Improvements in Multicylinder Two-Stroke Motors; and I do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

The invention relates to a multi-cylinder two stroke motor which to the advantages of perfect operation and efficiency adds that of a very economical construction, by reason of the restricted number of parts, of 20 which it is composed.

This motor is illustrated in a longitudinal view, one half in elevation, one half in section, in Figure 1 of the accompanying drawings.

Fig. 2 is a transverse view thereof, partly in section.

Fig. 3 is a detail view showing the lubricating grooves formed in the upper face of 30 the casing.

Fig. 4 is a detached view, in longitudinal elevation, of the crank shaft, of which Fig. 5 is an end view.

As an example a group of four cylinders 35 has been represented, but it will be readily understood that the number of cylinders may be varied.

The crank shaft *a* is provided with crank pins *a¹*, *a²*, *a³*, *a⁴*, equal in number to that of 40 the cylinders and carried by disks *b¹*, *b²*, *b³*, etc., provided with central bearings *c¹*, *c²*, *c³*, between the crank pins. In practice it is advantageous, especially for small motors, to form the crank shaft from a 45 round bar, without forging.

The crank shaft *a* rotates in a casing *d* divided by partitions *e*, and the gases cannot circulate from one compartment to the other. Further, the volume of each compartment as near as possible approximates that of the volume generated by the parts in motion, so as to reduce to a minimum the capacity of these compartments of the casing. Hollows are formed between the latter for the purpose of lightening the whole. 55 The upper face *d¹* of the casing is pierced

with orifices *a⁵*, just sufficient to allow the passage of the connecting rods *l*.

The same upper face *d¹* is hollowed with grooves *f* of crescent form (Figs. 1 and 3) 60 intended to collect the oil drawn up by the pistons and whence this oil proceeds by passages *g* to the crank shaft bearings.

The lubrication of the motor is effected by drop regulators on the admission or, preferably, by the incorporation of oil with the motor spirit in suitable proportions. The oil accumulates subsequently at the bottom of the compartments of the casing and it is picked up by the connecting rod heads 70 which it lubricates.

The cylinders *h*, which form one block, each bears an admission port *i*, placed in communication with the carburetor, and an exhaust port *j*, communicating with the 75 silencer or with the atmosphere. Further, each cylinder is provided with a pocket *k*, of suitable volume, having for its object to allow the gases which are situated beneath the piston when this is at the bottom 80 of its downward stroke to pass into the explosion chamber.

In turn, the pistons *m* are pierced with an opening *n* which places the pocket *k* of the cylinder in communication with the space 85 beneath the piston after the latter, in descending, has by its cylindrical part completely cut off the entrance to this pocket.

The pockets *k* in the wall of the cylinders and the openings *n* pierced through the pistons have for their object to as far as possible shorten the path traveled by the gases before their entrance to the explosion chamber. This arrangement, contrary to that which ordinarily exists, prevents their passage through the casing, which passage is here rendered difficult by the rapid rotation of the crankshaft and the connecting rods, which constitute a real blower, and it does away with the brake action of these 90 gases in the conduit by which they habitually ascend from the casing to the explosion chamber. The suppression of this circuit has also a beneficial effect on the carburation, the gases being no longer impoverished 100 in spirit to the detriment of the oil contained in the casing.

The pistons are provided with a deflector *o*, as shown in the drawing.

For ignition of this motor, the usual arrangements (a magneto rotating at twice the speed of motor) may be employed, or,

preferably the arrangement described in the specification of my prior application for Patent No. 176,127, filed June 21st, 1917. The drawing at *p*, in Fig. 1, shows the 5 magneto which the gearing *q*, *r* causes to rotate at twice the speed of the motor. *s* is the sparking plug.

What I claim as my invention, and desire to secure by Letters Patent, is:—

- 10 1. In a multicylinder engine comprising a crank casing, partitions dividing the casing into compartments, a crank shaft extending through the compartments with a crank in each compartment, a cover for each compartment having a piston rod opening, oil collecting grooves formed in the upper faces of the cover beneath the lower end of the piston, oil ducts extending from said grooves to the shaft-bearings and means to vent
- 15 20 gases from each compartment through the piston rod opening and the interior of the piston into the explosion chamber:

2. A multi-cylinder two stroke motor, comprising a crank casing, a plurality of partitions dividing the casing into a series 25 of compartments, a crank shaft extending through the compartments having bearing portions journaled in the partitions, and a pair of crank disks between each bearing working in each compartment, a piston rod 30 connected with each pair of crank disks, a cover for each compartment having an opening for the passage of the piston rods, arcuate oil-collecting grooves formed in the upper faces of the covers, and oil conduits extending through the partitions connecting the grooves with the shaft bearings.

In testimony that I claim the foregoing as my invention I have signed my name in presence of two subscribing witnesses.

MARCEL ACHILLE VIOLET.
